CLAIM

The ornamental design for a hair-cutting and make-up application guide, as shown and described.

DESCRIPTION

FIG. 1 is a perspective view of a hair-cutting and make-up application guide showing my new design;

FIG. 2 is a front elevational view thereof;

FIG. 3 is a rear elevational view thereof;

FIG. 4 is a top plan view thereof, the bottom plan view being identical to the side shown; and
FIG. 5 is a side elevational view thereof, the side opposite being identical to the side shown.

The broken lines shown on the drawing represent applied ornamentation.
